UNITED STATES PATENT OFFICE.

ERNST F. AUTENRIETH, OF NEW YORK, ASSIGNOR TO THE GLEN COVE MACHINE COMPANY, (LIMITED,) OF BROOKLYN, NEW YORK.

BELT-TIGHTENER FOR PLANING-MACHINES.

SPECIFICATION forming part of Letters Patent No. 401,677, dated April 16, 1889.

Application filed January 28, 1889. Serial No. 297,749. (No model.)

To all whom it may concern:

Be it known that I, ERNST F. AUTENRIETH, of New York, in the county and State of New York, have invented a certain new and useful 5 Improvement in Belt-Tighteners for Planing-Machines, of which the following is a specification.

My improvement relates to planing-machines, and particularly to that part thereof 10 embracing the driving mechanism.

I will describe in detail a planing-machine embodying my improvement, and then point out the novel features in claims.

In the accompanying drawings, Figure 1 is 15 a side elevation of such parts of a planing-machine as are essential to an understanding of my improvement. Fig. 2 is a plan or top view of the same. Fig. 3 is a sectional elevation, on an enlarged scale, looking in the 20 direction of the arrow, Fig. 1, and taken on the line $x-x$ of said figure. Fig. 4 is a detail, on an enlarged scale and partly in section, of certain parts. Fig. 5 is a view illustrating a modification.

25 Similar letters of reference designate corresponding parts in all the figures.

A designates a portion of the frame of the machine.

B designates a main or driving shaft, and 30 B' a main or driving pulley mounted thereon.

In Fig. 1 I have shown in dotted outline a belt, a, passing over the driving-pulley B' and an idler-pulley, B², and from thence to a pulley, B³, on a cutter-head shaft, b, upon 35 which is mounted a cutter-head B⁴.

B⁵ B⁶ represent presser-rolls driven by gearing or in any other suitable manner, but which, as they do not form part of my invention, I will not further describe.

40 Upon the driving-shaft B, outside the pulley B', is mounted a pulley, C.

C' designates an expansion-pulley. The expansion-pulley C' comprises a frame, C², of circular form. The frame C² is provided with 45 tangentially-extending slots C³, of which I have shown four. These slots form guideways for segments C⁵ of the expansion-pulley proper. The segments C⁵ are adapted to be moved nearer to or farther from the axis of 50 the pulley along said guideways. The outer edges of the segments C⁵ are arc-shaped, and

are grooved to receive a belt, G, passing through said grooves and about the pulley C. The inner ends of the segments C⁵ have pivotally connected to them links or rods d. 55 These links or rods extend rearwardly from the expansion-pulley approximately in line with the direction of movement of the segments C⁵, or, in other words, tangential to the axis of rotation of the pulley. At their 60 outer ends the links or rods are pivotally connected to a collar, E, which collar rotates with the shaft H, upon which the pulley is mounted, its rotation being due to a feather, d', on the shaft, which enters a suitable groove in the 65 collar. The said collar has a circumferential groove, E', and a yoke, F, is received within said groove. This yoke forms one arm of a bell-crank lever, F', fulcrumed upon a suitable support extending from the frame of the 70 machine. Pivotally connected to the other arm of the bell-crank lever is a rod, H'. The rod H', near its other end, is pivotally connected to a lever, H², constituting a shifting device, fulcrumed upon the frame A. The 75 upper portion of the lever H² is provided with an arc-shaped slot, e, through which extends a screw-threaded pin or stud, e'. A nut, e², engaging said pin or stud, may be employed to lock the lever H² in any position into which 80 it may be rocked. By swinging the lever H² in one direction or the other the segments of the expansion-pulley may be moved nearer to or farther from each other, thus increasing or decreasing the diameter of the pulley. When 85 it is desired to slow down, the diameter of the pulley will be increased. When it is desired to speed up, the diameter of the pulley will be decreased.

Of course varying the diameter of the pulley will cause variations in the tension of the belt G. In order to compensate for these variations, I employ a belt-tightener. This belt-tightener comprises pulleys g g', mounted upon arms g² g³, which arms extend from a 90 hub, g⁴, secured upon a rock-shaft, g⁵, which latter is journaled in the frame of the machine. Mounted upon said rock-shaft, and extending upwardly therefrom, is a lever, I. The upper portion of this lever terminates in 95 a handle. The lower portion is bifurcated, and the shaft g⁵ passes loosely through aper-

tures in said bifurcations. Between the bifurcations, and rigidly secured to the shaft g^5 , is a worm-wheel, I^1 . With this worm-wheel engages a worm, I^2 , journaled in portions f of the lever I , between the bifurcations thereof. Upon the shaft of the worm I^2 , outside the portions f of the lever, is a hand-wheel, I^3 . The belt G in this example passes under the pulley g and over the pulley g' . When it is desired to slacken or tighten the belt, the lever I is rocked in the proper direction for that purpose. If considerable slack is to be taken up, more, in fact, than could be taken up by the rocking of the lever I , (which might occur when the diameter of the expansion-pulley had been very much reduced,) the hand-wheel I^3 may first be manipulated to occasion the rocking of the rock-shaft g^5 , and consequently the shifting of the pulleys g g' to a desired extent, and then the lever I may be manipulated to tighten the belt to as great a degree as may be desired. Of course a similar operation may be performed where it is desired to occasion more slack in the belt than could be given through the movement of the lever I .

I employ a stop for automatically retaining the lever in a position into which it has once been adjusted. This stop consists of a cam, J , mounted upon a pin or stud extending from the lever I and provided with a handle, J' . The handle J' operates as a weight to maintain the cam in operative position.

J^2 designates an arc-shaped piece secured near its ends upon the upper side of the frame A , and passing about and in close proximity to the cam J . If said locking-piece occupies a position shown in Fig. 1, the lever I may be then moved freely toward the right of Fig. 1, and its return movement will be effectively prevented by the action of the cam J upon the arc-shaped piece J^2 , and it will not be necessary to use the hand for occasioning this locking, as it will occur automatically. When it is desired to move the lever in the other direction, however, the handle J' must be operated by hand to release the cam. If the handle be swung over on the other side, and the lever I be passed by the center or past the position shown in Fig. 1 and toward the left thereof, the cam will then operate automatically to prevent the movement of the lever in the other direction.

In Fig. 5 I have shown that a sliding bar, L , may be pivotally connected to the upper end of the lever I and slid through a guide-

way, L' . The cam J and arm J' may be employed in conjunction with this slider-bar to operate upon the upper side thereof for the same purpose as previously described.

It will be seen that by my improvement I provide means for adjusting the expansion-pulley by hand to a desired extent, and means for locking the same in such position after it has been so adjusted. At the same time I provide means for accurately tightening the belt, combining two movements operating through one mechanism, whereby a very accurate and perfect tightening of the belt is accomplished. At the same time I provide means for automatically locking the belt-tightener when it has been adjusted.

Although I have shown the cam J as mounted upon the lever and the pieces J^2 mounted upon the frame, it is obvious that these positions might be reversed.

What I claim as my invention, and desire to secure by Letters Patent, is—

1. The combination, with pulleys, of a belt passing about said pulleys, a belt-tightener, a rock-shaft upon which said belt-tightener is mounted, a worm-wheel on said rock-shaft, a worm engaging said worm-wheel, and a lever mounted upon the rock-shaft in which said worm is journaled, substantially as and for the purpose specified.

2. The combination, with pulleys, of a belt passing about said pulleys, a belt-tightener, a rock-shaft upon which said belt-tightener is mounted, a lever for operating said rock-shaft, and a main frame, said main frame and lever, the one being provided with a binding-surface and the other with a cam, constituting a lock adapted to bear upon said binding-surface to lock the lever in a position into which it has been adjusted, substantially as specified.

3. The combination, with pulleys, of a belt passed about said pulleys, a belt-tightener, a rock-shaft upon which said belt-tightener is mounted, a lever for operating said rock-shaft, and a main frame, said main frame and lever, the one being provided with a binding-surface and the other with a weighted cam adapted to bear upon said binding-surface to automatically lock the lever in a position into which it has been adjusted, substantially as specified.

ERNST F. AUTENRIETH.
